WRINGER MOP

Gilbert E. Bodimer, Indianapolis, Ind.

Application October 10, 1940, Serial No. 360,521

3 Claims. (Cl. 15—119)

This invention relates to a wringer mop of the general type disclosed in my co-pending application, Serial No. 307,306, filed December 2, 1939.

One object of the present invention is to provide a simplified and improved wringer mop of the type described.

Another object of the invention is to provide improved means for preventing fouling of the mopping material in the wringing operation.

Another object is to provide a simplified means of applying the wringing pressure.

In the type of wringer mop to which the present invention pertains, the mopping material is secured to a roller and a second roller parallel with the first is provided. The second roller is yieldingly urged toward the first and the first roller is rotatable to pass the mopping material between the rollers for wringing the same. In my prior application mentioned above, there is provided a roller of spiral cross section to which the mopping material is attached and which, because of its specific cross section, increases the wringing pressure toward the tip of the mopping material. In the present invention, similar results are obtained by an improved form of construction in which the roller itself is cylindrical and may thus be turned on a lathe, the additional squeezing effect required at the tip of the mopping material being provided by adding to the roller a protuberance in the form of a piece of curved sheet metal properly shaped to give the desired result.

In my prior application there is disclosed guard means formed on the frame of the structure to prevent the mopping material from fouling the bearings of the rollers. In the present invention the same result is obtained in a simpler manner by the provision of constraining means of a different type.

Other objects and features of the invention will be understood from the accompanying drawing and the following description and claims:

Fig. 1 is a side view of a wringer mop constructed in accordance with my invention. Fig. 2 is a view of the underside thereof.

In the preferred form of the invention shown by way of illustration in the drawing, there is provided a U-shaped frame structure 10 having downwardly projecting legs 11 and a ferrule 12 adapted to receive a mop handle 13 which may be of any suitable length. A roller 14 of cylindrical cross section has one end provided with a screw 15 journaled in one of the legs 11 and providing a bearing for said roller. A crank 16 is provided with a squared shank 17 projecting into

a suitable squared hole centrally disposed in the roller 14. Said crank is provided with a rounded portion 18 journaled in the second of the legs 11 and is provided with a knob 19 for rotating the same.

A curved piece of sheet metal 20, the shape of which is best seen in Fig. 1, extends longitudinally along the roller 14. One edge of said sheet metal is secured to the roller 14 as by screws 21 and forms a forward face 22 of relatively gentle slope and substantially continuous with the surface of the roller 12. The opposite edge of the piece 20 is curved at a steeper angle and is inset in a groove 23 in the roller 14. This portion of the piece 20 forms a rear face 24 having a steeper slope than the forward face 22 and intersecting the surface of the roller 14 at a relatively sharp angle. Mopping material 25 is provided and may be formed of fabric, cord or any other suitable material. One end 26 of said material is provided with a fabric sheath 27 which is secured to the roller 14 by means of screws 28 passing through the rear face 24 of the piece 20 and into the roller 14.

In order to restrain the edges 29 of the mopping material and prevent the same from working into the spaces between the ends of the roller 14 and the legs 11 of the frame, there are provided a pair of constraining bands 30. Each of said bands is preferably endless in form and passes about the sheath 27 adjacent the center thereof. Each of the bands 30 is thus secured in position when the mopping material is secured by the screws 28. The bands 30 extend downwardly and outwardly about the edges of the mopping material on one side thereof, as shown in Fig. 2, and each of said bands returns to its starting point by a similar path on the opposite side of the material. The bands are flexible in form and may be made of fabric, cord or any other suitable material and serve to prevent the edges 29 of the mopping material from leaving the face of the roller 14 when said roller is rotated by the handle 16.

A second cylindrical roller 31 is arranged in parallel relation with the roller 14 and is provided with screws 32 axially arranged and journaled in the ends of torsion springs 33. The opposite end of each spring 33 passes through a suitable opening in the associated leg 11 and is curved about the frame 10 as shown at 34. Said springs urge the roller 31 toward the roller 14 and provide the necessary pressure for wringing the mop material between said rollers. A suitable detent, preferably in the form of a flexible

member 35 engaging the crank arm 16, is provided to retain said crank arm in the position shown during the use of the mop.

In the wringing operation the detent 35 is released by pressing the same inwardly and the crank 16 is turned in the direction of the arrow in Fig. 1. The mopping material is thus passed between the rollers 31 and 14, the unsecured end 36 thereof passing between the roller 31 and the protuberance formed by the member 20. This portion of the material contains a large part of the water squeezed from the remainder of the material and requires the greater pressure to remove this water. The greater pressure is provided by the greater flexing of the springs 33 as the roller 31 rides on the forward face 22 of said member. The member 20 thus provides a similar wringing action to that of the spiral roller disclosed in my co-pending application before mentioned but the construction thereof is much simpler and the manufacturing cost and weight of the mop is greatly reduced. The provision of the constraining bands 30, the weight of which is practically negligible, obviates the necessity of adding metallic guards of any type to the frame structure or to the roller itself.

The invention has been described in one of its preferred forms, the details of which may be varied by those skilled in the art without departing from the scope of the invention as defined by the appended claims.

The invention claimed is:

1. In a wringer mop, a rotatable roller, mopping material having one end secured thereto, a second roller parallel with said first roller and yieldingly urged toward the same for wringing said mopping material therebetween, and flexible constraining bands secured adjacent the center of the secured end of said mopping material and extending diagonally downward and outward about the edges of said material on both sides thereof.
- 5 2. In a wringer mop, a rotatable roller, mopping material having one end secured thereto, a second roller parallel with said first roller and yieldingly urged toward the same for wringing said mopping material therebetween, and flexible constraining bands secured adjacent the secured end of said mopping material and extending diagonally away from said end and about the edges of said material on both sides thereof.
- 10 3. In a wringer mop, a rotatable roller, mopping material having one end secured thereto, a second roller parallel with said first roller and yieldingly urged toward the same for wringing said mopping material therebetween, and constraining means secured adjacent the center of the secured end of said mopping material and embracing the edges of said material at points remote from said secured end.

GILBERT E. BODIMER.
